Inventor:

Olive G. Henderson,
By Geo. C. Hutchinson
Atty.

UNITED STATES PATENT OFFICE.

OLIVE G. HENDERSON, OF ANN ARBOR, MICHIGAN.

COMBINED DESK AND CHAIR.

Application filed November 13, 1923. Serial No. 674,564.

To all whom it may concern:

Be it known that I, OLIVE GRACE HENDERSON, a citizen of the United States, residing at Ann Arbor, in the county of Washtenaw and State of Michigan, have invented certain new and useful Improvements in Combined Desks and Chairs, of which the following is a full, clear, and exact specification.

10 This invention relates to desks and chairs especially designed for use in school rooms, and constitutes an improvement on my former invention as disclosed in U. S. Patent No. 1,423,661, issued July 25, 1922.

15 One of the main objects of this invention is to provide a combined desk and chair which may be separated or knocked down for convenient transportation, and quickly and securely assembled or fastened together 20 for use in a class room or elsewhere. Another object is to provide improved means for hinging or attaching the cover of the storage compartment thereto, whereby said cover may be conveniently opened and 25 closed as required, and may always have its inner edge abutted closely against the adjacent edge of the desk top. Other objects will appear as the description proceeds.

The invention will be first hereinafter described in connection with the accompanying drawings, which constitute part of this specification, and then more specifically defined in the claims at the end of the description.

35 In the accompanying drawings, wherein similar reference characters are used to designate corresponding parts throughout the several views:

Figure 1 is a perspective view of a chair, 40 desk and storage compartment, all constructed substantially in accordance with this invention and shown separated from one another, as for convenient transportation.

45 Figure 2 is a detailed perspective view of the wooden strip constituting the arm of the chair.

Figure 3 is a perspective of the upper portion of the storage compartment with the cover partially opened.

50 Figure 4 is a fragmentary section of the storage compartment and its cover taken on the line IV-IV of Figure 1.

Figure 5 is a side elevation of the desk,

chair and storage compartment assembled. 55

Figure 6 is a section on the line VI-VI of Figure 5.

Figure 7 is a section on the line VII-VII of Figure 6.

Figure 8 is a perspective view of the upper portion of the storage compartment and adjacent part of the desk showing the cover of said storage compartment fully opened, and 60

Figure 9 is a section on the line IX-IX of Figure 8. 65

The chair 1 has a seat 2 and back 3, the latter preferably having two cross pieces or back rests 4 and 5. A shelf 6 is arranged below the seat being suitably secured between strips 7 extending between the rear legs 8 and the front legs 9 of the chair. Below the shelf 6 a foot rest 10 is mounted to slide being guided by the shelf and ledges 11 secured to the inner faces of the strips 7. Legs 12 are secured to the front edge portion of the foot rest 10 for supporting the same when it is projected in front of the chair to accommodate a small child, as fully explained in my Patent No. 1,423,661, referred to above. Said legs 12 also aid in supporting the front of the chair, the legs 9 preferably terminating just below the level of the shelf. The front of the chair is supported also, of course, by the desk when the latter is fastened thereto, as will be hereinafter explained. 70 75 80 85

The leg 9 at the right hand front corner of the chair extends above the seat 2, and said upwardly extending portion 13 thereof serves to support the angle portion of a metal bracket 14. Said bracket comprises two arms 15 and 16 arranged at right angles to one another, and said bracket including said arms is formed of angle iron reinforced by a gusset plate 17 at the angle or junction of said arms 15 and 16. The arm 15 extends from the upper end of the extension 13 of the leg 9 to the back of the chair and constitutes the right hand arm of said chair, while the arms 16 of the bracket extend parallel to the back and seat across the front of the chair. The chair has no arm at the left hand side because access thereto by the occupant is intended to be had at that side. 90 95 100 105

The desk 18 comprises a top 19 supported on front legs or supports 19, reaching to the

floor, and a bracket 20 having a vertical arm 21 arranged at the right hand rear corner of said desk top 19 and adapted to be bolted to the leg 9 and its upward extension 13 of the chair by bolts 22. Said vertical arm 21 of the bracket 20 terminates above the floor and substantially on the same level as said leg 9 of the chair. The bracket 20, which is made of angle-iron reinforced by a gusset plate 23, has a horizontal arm 24 secured below the rear edge of the desk top 19. When the desk and chair are assembled, said horizontal arm 24 of the bracket 20 is bolted to the horizontal arm 16 of the bracket 14 by bolts 25.

The legs 19 of the desk are connected together a short distance above their lower ends by one arm 26 of a bracket 27 which has another arm 28 connecting the lower end of the vertical arm 21 of the bracket 20 to the right hand leg 19. Said bracket 27 is made of angle iron and the arms 26 and 28 are arranged at right angles to one another and reinforced by a gusset plate 29. The left hand end of the desk top 19 is supported by a bracket 30 having a vertical arm 31 suitably fastened to the rear face of the left hand leg 19, and a horizontal arm 32, see Figure 6, suitably secured to the under surface of said desk top. The bracket 30 is also preferably made of angle-iron and reinforced at the juncture between its arms 31 and 32 by a gusset plate 33. It will be noted that the desk may be quickly attached to the chair by means of the bolts 22 and 25, the former bolts securing the vertical arm 21 of the bracket 20 to the right hand leg 9 and its extension 13 of the chair, while the latter bolts fasten the horizontal arm 24 of said bracket 20 to the front arm 16 of the bracket 14 of the chair. When thus assembled, the legs 19 at the front edge of the desk serve to support the front of the chair, and the rear legs 8 of the chair serve to support the rear edge of the desk.

It will be noted that the rear edge of the desk top 19 overhangs the vertical arm 24 of the bracket 20, so that when the desk and chair are assembled, said rear edge of the desk top covers the front arm 16 of the bracket 14. A slab 34 underlies the desk top 19 and extends beyond the same at the right hand end of the desk, providing a ledge 35 in which a groove 36 is formed for holding pens, pencils, pens and the like. The adjacent front corner of the desk top may be equipped with an inkwell 37.

A storage compartment or box 38 is adapted to be suitably secured to the right hand end of the desk by bolts 44, Figure 3, and said compartment has a cover 39 adapted to form a continuation of the desk top 19, the inner edge of said cover, when the latter is closed, abutting the right hand end of said desk top 19 and covering the ledge 35

and the groove 36 formed therein. The cover 39 of the compartment 38 has sliding hinge connection which permits said cover to always abut against the adjacent end of the desk top when said cover is closed, and which also permits the cover to be partially opened while remaining in a horizontal plane. The cover may thus be moved horizontally to a sufficient extent to permit access to the groove 36 in the ledge 35, and even to allow access to the left hand portion of the compartment 38 without raising said cover or swinging it out of its horizontal position.

Said sliding hinge connection between the cover 39 and storage compartment 38 includes a pair of metal strips 40 having horizontal slots 41 and secured to the inner faces of the end walls of said compartment so that said slotted portions extend above the top edge of the compartment and into grooves 42 in the undersurface of the cover 39. Pivot pins 43 are driven lengthwise of the cover 39 from both ends thereof so as to extend across the adjacent grooves 42 and through the slots 41 in the corresponding metal strips 40. Said pivot pins are preferably arranged about midway between the lateral edges of the cover, and the outer ends of the slotted portions of the metal strips 40 preferably project beyond the right hand lateral wall of the compartment 38, so that said cover may be moved horizontally to partially open the same until the pivot pins 43 engage the projecting ends of the slotted portions of the metal strips 40, as shown in Figure 3, and said cover may then be fully opened by swinging the same to a vertical position, as shown in Figures 8 and 9.

I claim:

1. The combination, with a chair having supporting legs of its own, an arm at one side of said chair formed by one arm of a horizontal angle bracket, the other arm of said bracket extending from said arm across the front of the chair, of a desk having supporting legs of its own, and means for detachably fastening said desk to said bracket arm which extends across the front of the chair, whereby the desk and chair may be secured together for use or knocked down for transportation.

2. The combination, with a chair having an arm at one side thereof formed by one arm of an angle bracket of metal, the other arm of said bracket extending across the front of the chair, of a desk, means for detachably fastening said desk to said bracket arm which extends across the front of the chair, said desk having its top overlapping said last mentioned bracket arm when the desk is secured thereto, and an arm plate secured to and overlying the bracket arm forming the arm of the chair.

3. The combination, with a chair having

- one of its front legs extended above the chair seat, of an arm for the chair supported by said leg extension, a rigid member also mounted on said leg extension and arranged 5 across the front of the chair, a desk having a vertical member to engage said chair leg and its extension, said desk also having a horizontal member to engage said rigid member extending across the front of the 10 chair, and means for detachably securing said vertical member to said chair leg and its extension and said horizontal member to said rigid member of the chair for the purpose specified.
- 15 4. The combination, with a chair, of an angle bracket having one arm arranged at one side of the chair to form a chair arm, the other arm of said bracket extending across the front of the chair, a chair leg 20 having an upward extension to support said bracket at the angle thereof, a desk having an angle bracket secured thereto, one arm of said bracket being disposed vertically to engage said chair leg and its extension, the 25 other arm of said desk bracket extending horizontally below the top of the desk to engage the arm of the chair bracket which extends across the front of the chair, and means for detachably fastening the desk bracket to said arm of the chair bracket and to said chair leg and its extension.
- 30 5. The combination, with a chair, of an angle bracket having one arm arranged at one side of the chair to form a chair arm, 35 the other arm of said bracket extending across the front of the chair, a chair leg having an upward extension for supporting said bracket at the angle thereof, a desk having an angle bracket with one arm disposed vertically to engage said chair leg and its extension, the other arm of said desk bracket extending horizontally below the desk top to engage the front arm of the chair bracket, means for detachably fastening said desk bracket to the front arm of the chair bracket and to said chair leg and its extension, desk legs reaching to the floor from the remote corners of the desk top, and an angle bracket having one arm connecting 40 said desk legs and the other arm connecting said desk legs with the lower end

portion of the vertical arm of said desk bracket.

6. The combination, with a chair, of an angle bracket having one arm arranged at 55 one side of the chair to form a chair arm, the other arm of said bracket extending across the front of the chair, a chair leg having an upward extension for supporting said bracket at the angle thereof, a desk having 60 an angle bracket with one arm disposed vertically to engage said chair leg and its extension, the other arm of said desk bracket extending horizontally below the desk top to engage the front arm of the chair bracket, 65 means for detachably fastening the desk bracket to the front arm of the chair bracket and to said chair leg and its extension, desk legs reaching to the floor from the remote corners of the desk top, an angle bracket 70 having one arm connecting said desk legs and the other arm connecting one of said desk legs with the lower end portion of the vertical arm of said desk bracket, and an angle bracket secured to the other one of 75 said desk legs for supporting the adjacent end of the desk top.

7. The combination, with a chair, having an arm at one side and a rigid member extending from said arm across the front of 80 the chair, of a chair leg having an extension above the chair seat for supporting said arm and rigid member, said chair leg terminating at its lower end at a distance above the floor, a desk having legs reaching to the 85 floor from its remote corners, a vertical member extending downwardly from the desk top to engage said chair leg and its extension, said vertical member also terminating at its lower end at a distance from 90 the floor, a horizontal member extending below the desk from the upper end of said vertical member to engage said front rigid member of the chair, and means for detachably fastening said vertical and horizontal 95 members of the desk to said chair leg and its extension and to said front rigid member of the chair, respectively.

In testimony whereof I have signed my name to this specification.

OLIVE G. HENDERSON.
